(57) **CLAIM**

The ornamental design for an automobile wheel, as shown and described.

DESCRIPTION

FIG. 1 is a perspective view of an automobile wheel in accordance with my new design (wherein the automobile wheel is shown with a tire mounted thereon);

FIG. 2 is a perspective view of the automobile wheel of FIG. 1 (wherein the automobile wheel is shown without a tire mounted thereon); and,

FIG. 3 is a front view of the automobile wheel of FIG. 1 (wherein the automobile wheel is shown without a tire mounted thereon).

The broken lines outlining the tire in FIG. 1 are for illustrative purposes only and form no part of the claimed design.

The broken lines outlining the rim portion of the automobile wheel in FIG. 2 are for illustrative purposes only and form no part of the claimed design.
